US00D950608S

(12) **United States Design Patent** (10) **Patent No.:** **US D950,608 S**
(45) **Date of Patent:** ** *May 3, 2022

(54) **INJECTOR**

(71) Applicant: **CATERPILLAR INC.**, Peoria, IL (US)

(72) Inventors: **Victor Iskander Yacoub**, Washington, IL (US); **Cory A. Brown**, Peoria, IL (US); **Satya Naga Deepak Pillarisetti**, Pontiac, IL (US); **Kevin J. Schreader**, East Peoria, IL (US); **Hoisan Kim**, Dunlap, IL (US); **Jianhua Zhang**, Dunlap, IL (US)

(73) Assignee: **Caterpillar Inc.**, Peoria, IL (US)

(*) Notice: This patent is subject to a terminal disclaimer.

(**) Term: **15 Years**

(21) Appl. No.: **29/788,886**

(22) Filed: **Aug. 10, 2021**

(57) **CLAIM**

The ornamental design for an injector, as shown and described.

DESCRIPTION

FIG. 1 is a front, top, left perspective view of an injector showing the new design;

FIG. 2 is a rear, bottom, right perspective view thereof;

FIG. 3 is front elevation view thereof;

FIG. 4 is a rear elevation view thereof;

FIG. 5 is a right-side elevation view thereof;

FIG. 6 is a left-side elevation view thereof;

FIG. 7 is a top plan view thereof;

FIG. 8 is a bottom plan view thereof; and,

FIG. 9 is an enlarged partial front elevation view as indicated in FIG. 3.

The broken lines of even length shown in the drawings illustrate portions of the injector that form no part of the claimed design.

1 Claim, 8 Drawing Sheets
